UNITED STATES PATENT OFFICE

FREDERIC M. CARD, OF BRIDGEPORT, CONNECTICUT, ASSIGNOR TO THE SINGER MANUFACTURING COMPANY, OF ELIZABETH, NEW JERSEY, A CORPORATION OF NEW JERSEY

SEWING MACHINE FOR JOINING FABRICS

Application filed May 28, 1930. Serial No. 456,380.

This invention relates to improvements in sewing machines and has for its primary object to provide a machine capable of efficiently joining materials, particularly rayon and knit-goods materials, by a stitched seam free from the bulkiness which is a characteristic of the butt-seams produced by sewing machines employed commercially for butt-seam joining of materials.

The foregoing and other objects and advantages in view, together with means whereby the same may be carried into effect, will best be understood from the following description of a preferred embodiment of the invention illustrated in the accompanying drawings, in which:

Fig. 1 is a longitudinal section, partly in front elevation, of the sewing machine. Fig. 2 is a sectional view substantially on the line 2—2 of Fig. 1. Fig. 3 is a front end elevation, partly in section, of the sewing machine with the upper portion of the bracket-arm omitted. Fig. 4 is a view substantially on the line 4—4 of Fig. 3. Fig. 5 is a view in side elevation, partly in section, of the presser-foot of the machine, including a sectional view of the throat-plate and feed-dogs. Fig. 6 is a top plan view of the throat-plate. Fig. 7 is a bottom plan view of the machine bed-plate. Fig. 8 is a sectional view of the bracket-arm supporting base, substantially on the line 8—8 of Fig. 1. Fig. 9 is a detail view in elevation of the primary feed-lever actuating crank. Fig. 10 is a rear side elevation, partly in section, of the feed-levers. Fig. 11 is a rear side elevation of the presser-foot and trimming mechanism. Fig. 12 represents perspective views partly in section, of the presser-foot and the supporting bracket thereof, one of the foot-plates being shown in dotted lines. Fig. 13 is a top plan view of the presser-foot work-engaging plates, omitting the guard blocks and the auxiliary foot. Fig. 14 represents perspective views of the feed-dogs and their carriers. Fig. 15 is a sectional view of the machine bracket-arm, substantially on the line 15—15 of Fig. 1.

Referring to the drawings, the sewing machine is shown as having a frame comprising a bed-plate 1 from one end of which rises a

tubular, supporting base 2 for the standard 3 of a tubular bracket-arm 4, which overhangs the bed-plate 1 and terminates in a head 5. Rising from the bed-plate 1, below the bracket-arm head 5, is a tubular work-supporting post 6 of which the front end comprises a swing-out closure-plate 7 pivotally connected by a hinge 8 to the base-flange 9 of the post 6. Suitably secured upon the upper end of the post 6 is a throat-plate 10, having a plurality of parallel feed-dog slots, as 11 and 12, and a transverse needle-slot 13. As illustrated more particularly in Figs. 5 and 6 of the drawings, the rear wall of the needle-slot 13 is partly cut away to provide a recess 14 in the upper face of the throat-plate inclined downwardly toward said slot 13, said recess 14 affording a clearance for a chaining-off finger 15 of which the underside is inclined upwardly toward its free end and which finger extends across the needle-slot 13 to overlie the recess 14 in spaced relation thereto, with the upper face of said finger substantially flush with the upper surface of the throat-plate. The chaining-off finger 15 is in the present case formed integral with a ridged fabric-margin supporting member 16 whose crest 17 is disposed centrally of and parallel with the line of seam formation and terminates in advance of the needle-slot 13 in a downwardly inclined surface 18 merging into the upper face of the chaining-off finger. The member 16 is removably disposed in a recess 19 formed in the upper face of the throat-plate between the front feed-dog slots 11 and 12, said member 16 being secured to the throat-plate by screws, as 20.

Journalized for rotation in suitable bearings provided in the bracket-arm 4 is a main actuating shaft 21, carrying at its outer end a driving pulley 22 and at its opposite end a crank-disk 23. This crank-disk serves to actuate in the usual manner a link 24 operatively connected with a vertically disposed needle-bar 25 journaled for endwise reciprocation in aligned bearing apertures provided in a swinging frame 26. The frame 26 is suspended from a fulcrum-pin 27 to swing about an axis transverse to the axis of rotation of the main-shaft 21 and derives its vibratory

movements about the fulcrum-pin 27 from actuating mechanism constructed substantially in accordance with the disclosure in the U. S. patent to C. F. Gray, No. 1,020,089, 5 Mar. 12, 1912. In general, a pitman 28 of which one end is connected with the frame 26 has at its opposite end a split-strap 29 embracing an eccentric 30. The eccentric 30 is adjustably secured upon a shaft 31 disposed 10 below and crosswise of the main shaft 21, which latter has gear connections with the transverse shaft 31 of a character such that the shaft 31 rotates at one-half the speed of rotation of the main-shaft. The needle-bar 15 25 carries at its lower end a needle 32, which through the described connections and in combination with work-feeding mechanism is reciprocated endwise and vibrated laterally to effect the production of zigzag stitches. 20 Cooperating with the needle 32, below the throat-plate 10, is a loop-taker 33 of the rotary-hook type, said loop-taker carrying a mass of under thread around which the needle-thread loops are cast in the formation of 25 lock-stitches. The actuating mechanism for the loop-taker 33 is substantially the same as disclosed in my prior Patent No. 1,729,994, Oct. 1, 1929. In general, the loop-taker is carried by a short, horizontally disposed shaft 30 34 carrying a bevel-gear 35 in mesh with a similar gear 36 upon the upper end of a vertically disposed, intermediate shaft 37 journaled in bearings provided within the post 6. At its lower end, the shaft 37 carries a bevel- 35 gear 38 driven by a gear 39 fixed upon the forward end of a loop-taker actuating shaft 40 journaled in suitable bearings provided at the under side of the bed-plate 1. The ratio of the gears 38 and 39 is such that the 40 vertical shaft 37 rotates twice for each rotation of the shaft 40. Secured upon the shaft 40 is a pulley 41 connected by a belt 42 with a pulley 43 upon the main-shaft 21, the shaft 40 rotating once for each rotation of said 45 main-shaft.

To intermittently advance the work past the needle, there is employed a differential feeding mechanism comprising a main feed-dog 44 operating through the feed-slots 11 in 50 the throat-plate and an auxiliary feed-dog 45 operating through one of the feed-slots 11 and the feed-slot 12. The main feed-dog 44 has a lateral shank 46 secured by screws, as 47, upon a primary feed-dog carrier 48 55 from which projects a reinforcing lug 49 underlying the shank 46 of the feed-dog. The feed-dog carrier 48 has a transverse aperture 50 entered by a pivot-stud 51 projecting laterally from the upper end of a vertically di- 60 rected, primary feed-lever 52. The feed-lever 52 intermediate its ends has a transversely apertured hub 53 pivotally mounted upon a fulcrum-pin 54 disposed crosswise of the direction of feed and suitably fixed in 65 bearing-bosses, as 55, within the frame post 6.

At its lower end, the feed-lever 52 is forked to embrace a slide-block 56 pivotally carried by a crank-arm 57 upon the forward end of a hollow main feed rock-shaft 58 journaled in bearing lugs, as 59, depending from the bed-plate 1. At its rearward end, the rock-shaft 58 carries a crank-arm 60 pivotally connected with the lower end of a pitman 61, of which the upper end has a strap 62 embracing an eccentric 63 adjustably secured upon the main-shaft 21 in substantially the manner disclosed in the U. S. patent to W. F. Dial et al., No. 718,988, Jan. 27, 1903. 70 The auxiliary feed-dog 45 also has a lateral shank 64 secured by screws, as 65, upon a feed-dog carrier 66 which likewise has a laterally extending reinforcing lug 67 underlying the shank 64. The carrier 66 has an up-standing ear 68 from which projects laterally a pivot-stud 69 entering an aperture in the upper end of a secondary feed-lever 70 disposed adjacent and extending in the same general direction as the primary feed-lever 52. The arrangement of the feed-levers and feed-dog carriers is such that adjacent sides 80 of the latter are disposed in sliding engagement with each other, whereby they are materially strengthened against lateral stresses. The feed-dog carriers are further steadied by an arm 70' projecting laterally from the secondary feed-lever 70 and bent upwardly at its free end to slidably engage the outer side of the primary feed-dog carrier 48. The carrier lugs 49 and 67 are arranged in substantial alignment in the direction of feed, the rear 90 lug 49 of the main feed-dog carrier overhanging the upper edge of the auxiliary carrier 66 adjacent the ear 68 thereof. 95 The secondary feed-lever 70 also has intermediate its ends an apertured hub 71 pivotally mounted upon the hub 53 of the feed-lever 52. At its lower end, the secondary feed-lever 70 is forked to embrace a slide-block 72 pivotally carried by a crank-arm 73 having a split hub 74 clamped upon the forward end of 100 an auxiliary feed rock-shaft 75 journaled in the main feed rock-shaft 58 with its opposite ends projecting beyond said rock-shaft 58. Suitably fixed upon the other projecting end of the auxiliary rock-shaft 75 is an arm 76 105 having a segmental groove 77 in the side thereof remote from the shaft end. Shiftably disposed in said groove 77 is a slide-block 78 pivotally connected with one end of a link 79 of which the opposite end is connected by a pivot-bolt 80 with the pitman 61 intermediate the ends thereof. 115 Consequently the rock-shaft 75 is actuated by the reciprocatory movements of the pitman 61 which impart rocking movements to 120 the shaft 58. However, the extent of movement of the rock-shaft 75 may be adjustably varied relatively to the rocking movements of the shaft 58. For this purpose, the slide-block 78 is also pivotally connected with one 125 130

end of a link 81 of which the opposite end is connected in like manner with a rock-arm 82 having a hub 83 fixed upon a sleeve 84 journaled upon a fulcrum-shaft 85 disposed substantially parallel with the main-shaft 21. The fulcrum-shaft 85 is fixed in suitable bearings provided in opposite walls of the bracket-arm base 2. The sleeve 84 carries a worm-wheel 86 in engagement with a worm 87 fixed upon an adjusting shaft 88 journaled in bearings in the front and rear walls of the base 2, said adjusting-shaft 88 being disposed crosswise of and above the rock-shaft 85. The front bearing for the adjusting shaft 88 comprises a shouldered bushing 89, suitably fixed in an aperture in the base 2 and integral with a segment-plate 90 disposed in front of said base 2. The segment-plate 90 has an arcuate slot 91 in which stop-members 92 and 93 are adjustably fixed. Suitably secured upon the end of the adjusting shaft 88, which projects forwardly beyond the segment-plate 90, is an adjusting-arm 94 having an offset end 95 overhanging the segment-plate 90. Threaded through the offset end 95 of the adjusting-arm is a securing screw 96 adapted to engage the circular periphery of said segment-plate, whereby the arm 94 may be adjustably clamped to the fixed segment-plate in different angular positions of said arm 94 and consequently in different positions of the slide-block 78 with respect to the axis of the rock-shaft 75.

Rising and falling movements are imparted to the feed-dogs in substantially the manner disclosed in my before mentioned prior Patent No. 1,729,994. In brief, this mechanism comprises a vertically disposed feed-lift bar 97 to the lower end of which is adjustably secured a fork 98 straddling an eccentric 99 upon the loop-taker actuating shaft 40. The feed-lift bar 97, which is journaled for endwise reciprocation in suitable bearings provided within the post 6, has at its upper end a fork 100 pivotally carrying between its members a pair of guide-blocks, as 101. The feed-dog carriers 48 and 66 are respectively provided with substantially horizontally directed slots 102 and 103 at their ends opposite to the pivotal connections of said carriers with the feed-bars, a guide-block 101 being slidably disposed within each of said slots 102, 103. It will be understood from the foregoing description that work-advancing and return movements are imparted to the feed-dogs 44 and 45 by the feed-levers 52 and 70, and that rising and falling movements are imparted to the feed-dogs about their pivotal connections with said feed-levers by the feed-lift bar 97. The extent of work-advancing movement of both feed-dogs may be determined by adjustment of the eccentric 63 upon the main-shaft 21, the stroke of the auxiliary feed-dog 45 being controlled independ-

ently of that of the primary feed-dog 44 by adjustment of the arm 94, as above described.

Opposed to the feed-dogs is a presser-foot carried by a main presser-bar 104 guided for vertically directed endwise movements in suitable bearings provided in the bracket-arm head 5. This main presser-bar is yieldingly depressed by the usual spring (not shown) and may be raised and lowered by any manually operated means commonly employed for this purpose. Upon the lower end of the presser-bar 104 is secured by a screw 105 a presser-foot supporting bracket 106, of which a portion of its front face has a rectangular recess 107 having its spaced side walls vertically disposed. Snugly seated in the recess 107 and secured therein by a screw 108 is the vertically disposed, flattened shank 109 of the presser-foot, this construction providing not only for ready removal of the presser-foot from the machine but also for accurately attaching it to the presser-bar. Projecting horizontally forward from opposite ends of the shank 109 are guide-members 110 and 111 provided with vertically aligned apertures in which are slidably disposed the vertically directed auxiliary presser-bars 112 and 113. The lower ends of these auxiliary bars carry horizontally disposed shoes 114 and 115 entering the channeled heels 116 and 117 of presser-foot plates 118 and 119, which respectively terminate in upturned toes 120 and 121 and are pivotally mounted upon the shoes 114, 115 by horizontally disposed pivot pins, as 122, passing through the spaced members of the U-shaped heels in a direction crosswise of the line of feed.

The foot-plates 118, 119 are yieldingly depressed independently of each other by springs 123 and 124 coiled about the auxiliary presser-bars 112, 113, said springs being interposed between the upper guide-member 110 of the presser-foot shank and collars 125 and 126 adjustably secured upon the bars 112, 113 to yieldingly rest upon the lower guide-member 111 and thereby limit the downward movement of the foot-plates 118, 119. The collars 125, 126 each have a depending guide-fin 127 slidably disposed in a suitable guide-slot in the lower guide-member 111, whereby the bars 112, 113 are confined to vertically directed movements.

The foot-plates 118, 119 are spaced from each other beginning from the toes 120, 121 thereof to form a fabric-margin slot 128 which terminates at a point directly in front of the needle path, at which point the adjacent edges of the foot-plates curve inwardly into abutting relation to together form a split guide-web 129 which serves to deflect under the presser-foot the upwardly directed fabric margins passing through the slot 128. The guide-web 129 which also terminates in front of the needle-path, is comparatively 130

narrow in the direction of seam formation, the adjacent edges of the foot-plates rearwardly of said guide-web being cut away to merge into the foot-plate heels 116, 117.

5 This construction of the foot-plates provides a substantial space between the heels 116, 117 thereof, in which space is disposed an auxiliary or chaining-off foot 130 having its toe spaced rearwardly from the guide-web 129 in the line of seam formation to provide a needle slot 131 in the presser-foot. The auxiliary foot 130 is preferably rigidly carried by a shouldered guide-bar 132 of which the lower portion is slidably disposed in a 10 vertically directed aperture provided in a guide-block 133 upon the presser-foot shank 109. The reduced upper end of the guide-bar 132 is disposed within a screw-bushing 134 adjustably threaded into the upper side 15 of the guide-block 133, a spring 135 coiled about the reduced portion of the guide-bar being interposed between the bushing 134 and the shoulder of the guide-bar. The foot 130 has an upturned heel 136 which overlies 20 a bent stop-plate 137 secured by a screw 138 upon the rear side of the presser-foot shank 109, whereby downward movement of the foot 130 under the action of the spring 135 is limited. It will be observed that the crest 25 17 of the fabric-margin supporting member upon the throat-plate rises substantially centrally of the presser-foot slot 128 and that it is in alignment with the auxiliary foot 130.

30 The machine is provided with a mechanism 35 for trimming the upturned fabric-margins passing through the presser-foot slot 128, said mechanism in the present instance including a horizontally disposed ledger-blade 139 and a horizontally vibratory cutting-blade 140 resting upon the ledger-blade, the cutting edges of said blades meeting in shearing relationship directly above the foot slot 128 and in advance of the guide-web 129.

35 The ledger-blade 139 is rigidly clamped in 40 a split head 141 of a collar 142 suitably secured upon the lower end of a vertically slideable rod 143 journaled in spaced lugs 144 formed on an auxiliary bracket 145 secured by screws as 146, upon a primary bracket 147 45 fixed by screws, as 148, upon the rear side of the machine head 4. The rod 143 is restrained against oscillation about its longitudinal axis by a forked guide-collar 149 adjustably carried by said rod and embracing 50 a guide-rib 150 on the bracket 145. Underlying the collar 149 is a lip 151 projecting laterally from a stop-member 152 secured for vertical adjustment upon the presser-foot supporting bracket 106. The stop-member 55 60 65 70 75 80 85 90 95 100 105 110 115 120 125 130

portions of the work. The stop-member 152 also functions to raise the trimmer-blades when the presser-foot is raised for insertion and removal of work. It will be observed that the described construction furthermore 70 provides for adjustably raising and lowering the trimming position with respect to the work-support.

The cutting-blade 140 is rigidly clamped in a holder-collar 153 carried by a rod 154 slidably disposed in vertically aligned apertures provided in spaced lugs, as 155, projecting forwardly from a rock-arm 156. A spring 157 is coiled about the rod 154 and is interposed between the upper of the lugs 155 and a forked guide-collar 158 adjustably secured upon the rod above the lower lug 155, whereby the cutting-blade 140 is yieldingly urged into engagement with the ledger-blade 139 which it overlies. The rock-arm 156 has a 80 split hub 159 clamped by a screw 160 upon a sleeve 161 journaled for oscillatory movements upon a vertically disposed fulcrum-pin 162 fixed in vertically spaced bearing-lugs, as 163, upon the primary bracket 147. 85 Projecting laterally from the upper end of the sleeve 161 is an arm 164 connected by an extensible link 165 with an arm 166 depending from one end of a horizontally disposed rock-shaft 167 journaled in a bracket 168 suitably secured to the underside of the machine bracket-arm 3. The other end of the rock-shaft 167 carries a crank-arm 169 pivotally connected with a pitman 170 having a strap embracing an eccentric 171 upon the 90 main shaft 21. It will be observed that the ledger-blade 139 and its supporting means can be removed from the machine independently of the other blade supporting means by detaching the auxiliary bracket 145 from the machine bracket-arm, and that the entire trimmer-blade supporting mechanism can be removed as a unit from the machine by detaching the primary bracket 147.

95 Secured upon the foot-plates 118, 119, for 100 individual detachment therefrom and disposed adjacent to the fabric-slot 128 therebetween, are guard-blocks 172 and 173 provided in their under faces with recesses 174 and 175 affording the necessary clearance for 105 the trimmer-blades 139, 140, which project through said recesses, to allow the foot-plates 118, 119 to rock slightly about their pivotal supports during the passage of the work without affecting the trimming position. The 110 side face 176 of the guard-block 173 adjacent to the slot 128 is gradually curved towards its rearward end to extend across said slot 128 and merge with the rearward wall of a slot 177 formed in the guard-block 172, whereby 115 the trimmed-off portion of the work is diverted laterally out of the seam line. Conforming with the diverting-surface curvature of said blocks and disposed directly 120 thereabove in its operative position so as to 125 130

cooperate with said surface in deflecting the trimmed-off fabric margins, is a diverter-blade 178 having its shank 179 bent to closely embrace the ledger-blade carrying collar 142.

- 5 The curved shank 179 of the diverter blade has a horizontally elongated slot 180 entered by the stop-screw 181 threaded into said collar and passing through a friction washer 182. This construction provides simple supporting means for the diverter-blade, permitting the blade to be readily swung into and out of operative position. Because the function of diverter-blades of this character is well known, the drawings show the blade 15 as swung into its ineffective position to more clearly illustrate the mechanism in part obscured by the blade in its operative position.
- In its passage to the needle from a suitably located supply, the needle-thread is led 20 through guide apertures, as 183, formed in spaced thread-guiding arms, as 184, suitably secured upon the removable cover-plate 185 of the machine bracket-arm. Between said arms, the thread is passed through an aperture 25 186 in a pull-off lever-arm 187 projecting through a suitable opening (not shown) in the cover-plate 185. The pull-off lever is secured intermediate its ends upon a rocking fulcrum-pin 188 journaled in a pair of brackets, as 189, suitably fixed to the underside of said cover-plate 185. At its lower end, the pull-off lever is bifurcated to provide a fork 190 straddling an eccentric 191 upon the main-shaft 21. Adjustably secured upon the fulcrum-pin 188, as by a set-screw 192, is an arm 193 positioned to engage the lower end of a vertically disposed nipper-pin 194. Secured upon the upper end of the pin 194 is a clamp-disk 195 urged by a spring 196 into engagement with the upper face of a nipper-member 197 fixed upon the cover plate 185. The thread-nipper referred to is located between the pull-off arm 187 and the usual take-up arm 198, the needle thread after leaving the 40 pull-off device passing under the clamp-disk 195 and through the thread-guide 199 to the take-up.

From an inspection of Fig. 2 of the drawings, it will be observed that the pull-off arm 187 moves forwardly from between the thread-guides 184 to pull thread from the supply at the time that the nipper-pin 194 is depressed to cause the clamp-disk 195 to nip the thread and that the nipper-pin 194 is 50 raised by the arm 193 during the return movement of the pull-off arm 187 to give up the thread pulled from the supply.

Any suitable or well known means may be employed for releasing the thread-nipper, as 55 for instance for the purpose of removing the work from the machine. In the present machine there is employed a nipper-releasing lever 200 which is fulcrumed upon the machine bracket-arm 4 and has operative connections (not shown) with the usual presser-

foot lifting means. The lever 200 has a wedge-shaped nose 201 positioned to enter between the clamp-disk 195 and the nipper-member 197 when the presser-foot is raised, to thereby release the thread.

In order to join fabric plies by a butt seam, the marginal portions of such plies upon the work-supporting post are directed upwardly to pass through the presser-foot slot 128, whereupon the shearing elements 139, 140 trim said margins and the trimmed off surplus is directed laterally out of the path of the needle by the merging diverting surfaces of the guard-blocks 172, 173, aided by the diverter blade 178. The trimmed off margins of the plies are then forced downwardly into abutting relation by the presser-foot guide-web 129 during the advance of the work by the feeding mechanism. As the auxiliary feed-dog 45 operates only at one side of the line of seam formation, it acts only upon one of the fabric-plies and accordingly this ply may be more or less shirred by adjusting the stroke of said auxiliary feed-dog with respect to that of the main feed-dog 44. It will be 90 understood, of course, that in order to full or gather both fabric plies it is only necessary to employ an auxiliary feed-dog shaped to extend upon opposite sides of the line of feed.

The abutting fabric plies are joined by a 95 zigzag-stitch seam formed by the vertically reciprocating and laterally vibrating needle 32 in conjunction with the loop-taker mechanism beneath the throat-plate. The presser-foot plates 118, 119 are each capable of riding 100 uneven portions of the work by reason of their pivotal and bodily yielding support upon the presser-foot body and can readily adapt themselves to differences in thicknesses of the fabric plies being joined. The auxiliary foot 130 rides the seam formed and, as usual, opposes a portion of the feed-dog in the absence of work to assist in chaining off.

While the seam formed by the present machine is not in itself novel, it presents advantageous characteristics over the multiple-needle, cross-thread seam employed for joining fabric sections, in that it is less bulky, requires only a relatively small quantity of thread and has more than ample strength to securely 115 join the fabrics. The present machine is particularly designed to conveniently handle the work and to join fabric sections at a high speed of operation.

Having thus set forth the nature of the 120 invention, what I claim herein is:—

1. Feeding mechanism for sewing machines including a feed-dog carrier, a feed rock-shaft, operative connections with said rock-shaft for transmitting work-advancing 125 and return movements to said feed-dog carrier, a crank-arm carried by the feed rock-shaft, an actuating element, a shiftable member connecting said element and the crank-arm, and means for shifting said member 130

endwise of said crank-arm for adjustably determining the extent of work-advancing movement of the feed-dog carrier comprising, a rock-arm operatively connected with 5 the member, a feed-adjusting shaft, intermeshing gears coaxial with said feed-adjusting shaft and rock-arm, and means for actuating the feed-adjusting shaft.

2. Feeding mechanism for sewing machines including a feed-dog carrier, a feed rock-shaft, operative connections with said rock-shaft for transmitting work-advancing and return movements to said feed-dog carrier, a crank-arm carried by the feed rock-shaft, an actuating element, a shiftable member connecting said element and the crank-arm, and means for shifting said member endwise of said crank-arm for adjustably determining the extent of work-advancing 20 movement of the feed-dog carrier comprising, a rock-arm operatively connected with the shiftable member having its fulcrum-axis substantially parallel with the feed rock-shaft, a feed-adjusting shaft disposed transversely of said rock-arm fulcrum-axis, worm-gearing connecting the feed-adjusting shaft with said rock-arm, and an operating member carried by the feed-adjusting shaft.

3. Feeding mechanism for sewing machines including a feed-dog carrier, a feed rock-shaft, operative connections with said rock-shaft for transmitting work-advancing and return movements to said feed-dog carrier, a crank-arm carried by the feed rock-shaft, an actuating element, a shiftable member connecting said element and the crank-arm, and means for shifting said member endwise of said crank-arm for adjustably determining the extent of work-advancing 40 movement of the feed-dog carrier comprising, a rock-arm operatively connected with the shiftable member having its fulcrum-axis substantially parallel with the feed rock-shaft, a feed-adjusting shaft disposed transversely of said rock-arm fulcrum-axis, worm-gearing connecting the feed-adjusting shaft with said rock-arm, a stationary segment-plate, an operating member carrier by the feed-adjusting shaft, means for adjustably 50 securing said operating member to the segment-plate in angularly different positions of said feed-adjusting shaft, and stop-members carried by said segment-plate for adjustment into different positions in the path 55 of movement of said operating member.

4. In a sewing machine having a bed-plate, a vertically disposed work-supporting post rising from said bed-plate, a reciprocating needle, a loop-taker housed within said post, 60 a pair of feed-dog carriers disposed within the upper end of said post with adjacent sides of said carriers in sliding engagement, a pair of vertically directed feed-levers within the 65 post pivotally connected at their upper ends

with the feed-dog carriers, a coaxial pivotal support for said feed-levers intermediate the ends thereof, actuating mechanism connected with the lower ends of said feed-levers for imparting work-advancing movements to the feed-dog carriers, a vertically reciprocatory feed-lift bar within the post, means for actuating said bar, and connections with the feed-lift bar for imparting rising and falling movements to both of the feed-dog carriers. 70 75

5. A differential feeding mechanism for sewing machines comprising main and auxiliary feed-dog carriers disposed with adjacent vertical sides thereof in sliding engagement, a pair of vertically disposed feed-levers 80 pivotally connected with said carriers, one of said feed-levers having a bent arm slidably embracing both of the feed-dog carriers, a coaxial pivotal support for the feed-levers, actuating mechanism for rocking said feed-levers including means whereby the stroke of one feed-dog carrier may be varied with respect to that of the other, and a vertically reciprocatory feed-lift bar for imparting rising and falling movements to both of said 85 feed-dog carriers. 90

6. In a sewing machine having a bed-plate, a vertically disposed work-supporting post rising from said bed-plate, a reciprocating needle, a loop-taker housed within said post, a rotary loop-taker actuating shaft journaled beneath the bed-plate, a pair of feed-dog carriers disposed within the upper end of the post, a pair of vertically disposed feed-levers within the post pivotally connected at their upper ends with the feed-dog carriers, a coaxial pivotal support for said feed-levers intermediate the ends thereof, coaxial feed rock-shafts journaled beneath the bed-plate operatively connected with the feed-levers, means for actuating said rock-shafts, means accessibly presented to an operator in the operative position of the machine for effecting adjustment of the stroke of one feed-lever with respect to that of the other, a vertically reciprocatory feed-lift bar within the post, and means for actuating said feed-lift bar from the loop-taker actuating shaft. 100 105 110

7. Differential feeding mechanism for 115 sewing machines comprising, main and auxiliary feed-dogs, means for imparting rising and falling movements to said feed-dogs, and means for imparting work-advancing and return movements to the feed-dogs including 120 a pair of coaxially arranged feed rock-shafts, a pitman operatively connected with one of said rock-shafts, a crank-arm carried by the other rock-shaft, a member shiftable disposed upon said crank-arm, a link-connection between said member and said pitman, a rock-arm operatively connected with the shiftable member, and adjusting means including gear connections with said rock-arm for determining the effective action of said link-connec- 125 130

tion upon the rock-shaft crank-arm, whereby the extent of work-advancing movement of one feed-dog may be adjusted with respect to that of the other feed-dog.

5 In testimony whereof, I have signed my name to this specification.

FREDERIC M. CARD.
